JOHN VAN BUREN, OF BROOKLYN, NEW YORK.

SEALING MECHANISM FOR CONTAINERS.

Application filed November 5, 1926. Serial No. 146,428.

This invention relates to sealing mechanism for containers.

One of the most difficult problems in handling greasy or oily substances in cans or containers having removable covers, is to prevent the substance from leaking out of the can around the cover and to prevent air from leaking in thereby causing the substance to deteriorate. The usual method of procedure is to place the cover on the cover end of the can or container, then place the substance in the can and permanently close the other end of the container.

It has been found that an effective seal around the cover can be obtained by crimping the cover or forcing the cover over a liner of cellophane or thin transparent material in the nature of paper. This material is, however, very difficult to handle as it tears and curls very easily.

This invention has for its salient object to provide means for applying material, such as that specified, to cans or containers.

Another object of the invention is to provide cutting mechanism for cutting the material to fit the cans or containers after it has been fed in a strip over the top of the can.

Another object of the invention is to provide in a machine of the character specified, means for insuring the proper and efficient feeding of the strip of material to the containers.

Another object of the invention is to provide in a machine of the character specified, means for insuring the proper and efficient feeding of the viscous material or grease to the tops of the containers.

Further objects of the invention will appear from the following specification taken in connection with the drawings, which form a part of this application, and in which

Fig. 1 is a longitudinal section of a machine constructed in accordance with the invention taken substantially on line 1—1 of Fig. 2, certain parts being omitted for the sake of clearness;

Fig. 2 as a top plan view of the device shown in Fig. 1, this view being partly in section on line 2—2 of Fig. 1;

Fig. 3 is an enlarged sectional elevation taken substantially on line 3—3 of Fig. 2;

Fig. 4 is an enlarged elevation taken substantially on line 4—4 of Fig. 1;

Fig. 5 is a sectional elevation taken substantially on line 5—5 of Fig. 4;

Fig. 6 is a sectional elevation taken substantially on line 6—6 of Fig. 2;

Fig. 7 is a sectional elevation taken substantially on line 7—7 of Fig. 5; and

Fig. 8 is a sectional elevation of one of the containers showing the cellophane disk on the upper end or top thereof.

The invention briefly described consists of a machine comprising mechanism for supporting and feeding a plurality of containers, such as cans, means for feeding an elongated or continuous strip of material along the tops of the containers and means for severing the strip between adjacent containers. In the particular embodiment of the invention shown, a lubricant or grease is fed to the tops of the containers prior to the positioning thereover of the strip of material, the grease functioning to prevent the material, such as cellophane, from curling or cracking. Another feature embodied in the machine is the mounting of the cutting mechanism and presser feet for holding the strip against the tops of the containers during the cutting operation on a carriage movable with the containers and strip. In other words, the pressing and cutting mechanism coacts with one pair of adjacent containers to cut the strip between said containers and during this operation, moves forwardly at substantially the same rate of speed as the travel of the containers and strip. The carriage on which the cutting and pressing devices are mounted then moves back to a position to coact with the next pair of adjacent containers which in the meantime have been continuously advancing.

Various novel features are incorporated in the grease feeding, strip feeding, strip

holding and strip cutting mechanisms, and these will be brought out in more detail in the following description.

5 Supporting and feeding mechanism for containers.

In the particular embodiment of the invention illustrated, the machine is supported on uprights or pedestals 10 and 11 and 10 the supporting bed for the machine comprises a pair of longitudinally extending I beams or supports 12 and 13. A frame 14 is mounted intermediate the I beams 12 and 13 and is supported thereby.

15 The containers or cans are mounted on individual supports 16, each support comprising a base 17 having a boss 18 depending therefrom and lugs 19 depend from the boss. A cylindrical portion 20 extends upwardly 20 from each of the bases and has its upper end 21 beveled as shown in Fig. 1.

The lugs 19 are mounted on the link pins 25 of an endless chain 26 and the chain is supported on rails 27 and 28 which are engaged by rollers 29 and 30 mounted on the outer ends of the pins 25. The rollers are held on the tracks or rails 27 and 28 by strips 31 and 32 positioned above the rollers.

The chain is mounted on a pair of sprockets 35 and 36 carried by shafts 37 and 38 supported in suitable bearings at the ends of the I beams 12 and 13. The shaft 38 has a sprocket 40 at one end thereof connected by a chain 41 to a sprocket 42 mounted at one 35 end of a shaft 43. The shaft 43 is the drive shaft and may be driven from any suitable source of power. The cans or containers are fed to the endless chain and can supports thereon by a chute 45, the end of the chute as 40 shown in Fig. 2 being adapted to place the cans in a position to be engaged by the can supports in the manner shown in Fig. 1. In order to hold the cans in position as they are being engaged by the can supports, a flexible 45 and preferably resilient strip of material 46 is supported on a bracket 47 and is held in any suitable manner as by weights 48 in a position to engage the upper ends of the cans as they are being placed on the can supports. 50 The operation of this strip should be clear from the showing in Fig. 1.

From the foregoing description it will be seen that the cans or containers will be picked up by the chain and can supports thereon and will be fed continuously through the machine by the chain and sprocket drive, the cans being positioned with their upper ends disposed substantially in the same plane or in alinement.

60 Lubricant or grease applying mechanism.

Cellophane paper, which is a very thin paper substance, is a difficult material to handle since it tends to curl and is also very brittle and fragile and is easily cracked. In

order to facilitate the handling of this paper and to prevent curling, cracking or breaking, a thin coating of grease or lubricant is applied to the tops of the cans. This grease is mounted in a receptacle 50 supported above the path of travel of the containers and the grease is fed to the tops of the cans or containers by feed rolls 51, 52 and 53. The roll 52 engages the rolls 51 and 53 and is adjustably mounted in eccentric bushings 55. The roll 51 dips into the grease or other substance in the receptacle 50 and transfers a film of grease to the roll 52 which in turn transfers the film to the roll 53 by means of which the grease is applied to the tops of the cans. From the showing in Fig. 2 it will be noted that the rolls 51, 52 and 53 gradually decrease in length. This change in dimensions is made for the purpose of returning any excess lubricant or grease from the roll 53 to the receptacle and this return is effected in the following manner.

The roll 52 will receive from the roll 51 a thin film of grease and will transfer this thin film to the roll 53. Any grease that extends beyond the ends of the roll 53 will be taken up by the roll 52 which extends beyond the ends of the roll 53 and will be delivered to the roll 51 which extends beyond the ends of the roll 52. The roll 51 will thus return this excess grease to the receptacle 50.

From the foregoing explanation it will be clear that a thin coating of grease or lubricant will be applied to the top of each can or container as it passes beneath the roll 53.

Strip feeding mechanism.

As shown in Fig. 1, a supply roll 60 of paper or other suitable material is supported in brackets 61 above the path of movement of the cans or containers. The paper is fed into engagement with the tops of the containers or cans by means of feed rolls 63, 64 and 65 which are geared together as shown at 66, 67 and 68 in Fig. 2 and are driven in a manner hereinafter described.

The material or paper strip 70 is led beneath the roll 63 around the roll 64 and between the roll 65 and the roll 64 and leaves the roll 64 at the bottom thereof. The roll 64 as clearly shown in Figs. 1 and 3 extends below the rolls 63 and 65 and presses the paper into contact with the upper ends of the cans or containers.

In order to maintain the proper feed for the paper and to take up any slack therein, the rolls 63 and 65 have portions 71 and 72 of the periphery thereof cut away or slabbed off. In Fig. 3 it will be noted that the portion 71 of the roll 63 is positioned opposite the roll 64. In this position of the rolls no feeding action between the rolls 63 and 64 will take place but the feeding action between the rolls 64 and 65 will continue and

any slack between the roll 64 and the supply roll 60 will be taken up by the feed between the rolls 64 and 65. It will be evident that when the cutaway or recessed portion 72 of the roll 65 is disposed opposite the roll 64, the feed between these two rolls will be interrupted and any slack between the coacting portions of the rolls 63 and 64 will be taken up.

10 *Strip severing mechanism.*

The strip severing mechanism is so constructed that the strip will be severed between the two adjacent foremost cans or containers without requiring the interruption of the continuous feed of the containers through the machine. This is accomplished in the following manner.

15 The strip severing mechanism is mounted on a carriage comprising a pair of U-shaped frames 80 and 81 mounted on bases 82 and 83 which are slidably mounted in guideways 84 and 85 carried by the upper ends of the I beams 12 and 13.

20 The carriage is reciprocated in the following manner. Each of the bases 82 and 83 has pivoted to depending lugs 86, a link 87, the other end of the link being pivoted to an arm 88. The arms 88 are mounted on a shaft 89. This shaft has secured to one end thereof an arm 90, the other end of the arm having secured thereto a roller 91 positioned in a cam groove 92 of a cam 93 carried by the shaft 43. The cam 93 is so constructed 25 that the rotation thereof will cause the carriage and cutting and presser mechanism carried thereby to move forwardly at substantially the same rate of speed as the travel of the containers and to coact with adjacent containers and sever the strip between said containers.

30 From the showings in Figs. 1 and 2 it will be seen that the U-shaped frames 80 and 81 have secured thereto and extending inwardly therebetween guide blocks 95 and 96 between which is slidably mounted a frame 97 which has secured to its lower end a pair of presser feet 100 and 101 adapted to press the paper against the tops of the adjacent cans during the cutting operation. The presser feet have secured thereto stationary knives 105 and 106. These knives are curved longitudinally and extend across the strip, the knife carried by one presser foot being disposed opposite to the knife carried by the other presser foot. The stationary knives and presser feet on which they are mounted are adapted to reciprocate vertically during the operation of the machine in such manner that they will coact with a pair of adjacent cans during the cutting operation and will then be raised out of operative position until the carriage has been moved to a position to coact with the next pair of adjacent cans whereupon the presser feet will then

again descend into operative position. The operating connections for the presser feet will be explained after the operation of the movable or rotary cutting knives has been set forth.

35 The movable cutting mechanism comprises two sets of blades adapted to coact with the stationary knives or relatively stationary knives carried by the presser feet. These two sets of blades are mounted at the longitudinal edges of the strip 70 on shafts 110 and 111. From the showing in Figs. 2 and 5 it will be seen that blades 112 and 113 are mounted on the shaft 110 and coact with the fixed blades 105 and 106 carried by the 40 presser feet. Blades 115 and 116 are mounted on the shaft 111 and are also adapted to coact in shearing relation thereto with the blades 105 and 106. The movable blades are shaped to conform to the shape of the relatively stationary blades carried by the presser feet and are so constructed that the movable blades will in conjunction with the stationary blades shear the strip and entirely 45 sever the strip between its longitudinal edges. It will be noted that the stationary blades carried by the presser feet are positioned above the strip whereas the movable blades move upwardly from below the strip. Both the stationary and movable blades are preferably formed of resilient material.

50 The shafts 110 and 111 have mounted thereon bevel gears 120 and 121 which mesh with gears 122 and 123 carried by a shaft 124. The shaft 124 has secured to one end thereof 55 a sprocket 125 which is connected by a chain 126 to a sprocket 127 mounted on the shaft 43.

55 The presser feet are vertically reciprocated by means of an arm 130 carried by a shaft 131 and having one end thereof positioned in an opening 132 in the frame 97. The shaft 131 also has secured thereto an arm 135 having a roller 136 at its opposite end engaging a cam 137 mounted on the shaft 110. From the showing in Fig. 4 it 60 will be seen that the roller 136 is disposed in a depression in the cam 137 permitting the presser feet to drop into a position to press the paper against the tops of the cans. The movable cutting knives in Fig. 4 are 65 moving upwardly in coaction with the stationary cutting knives carried by the presser feet to sever the strip between the adjacent cans. It will be evident from the showing in Fig. 4 that the presser feet will be raised after the movable knives have functioned to 70 sever the strip and during the movement of the carriage into coacting position relative to the next set of adjacent cans which in the meantime have been advancing.

75 The feed rolls for the grease or lubricant and for the paper strip may be driven in any desired manner but in the form of the invention illustrated, the following driving connections are provided.

100

105

110

115

120

125

130

As above explained, the three rolls for feeding the paper 63, 64 and 65 are provided with intermeshing gears 66, 67 and 68. The central gear 67 is mounted on a shaft 140 which carries a sprocket 141 connected by a chain 142 to a sprocket 143 carried by shaft 144. Shaft 144 has secured thereto a gear 145 which meshes with the gear 146 carried by the main drive shaft 43.

10 The shaft 140 also has secured thereto a sprocket 150 connected by a chain 151 to drive a sprocket 152 mounted on the shaft 153 which carries the feed roll 53. The rolls 52 and 51 are driven from the shaft 153 by 15 means of intermeshing gears 154, 155 and 156.

Any suitable means may be provided for removing the containers with the disks thereon from the machine. In Fig. 1 there 20 is shown a wheel 160 having arms 161 adapted to engage the cans and to remove the cans from their supports. The wheel 160 is mounted on a shaft 162 driven by a worm and worm gear driving connection 163, 164 25 from the shaft 38.

Operation.

The machine above described operates in the following manner. The tubular containers or cans which as shown are open at both ends are fed into the machine by a chute 45 and are taken up successively by the can supports 16 and 17. These supports are fed by the chain in such a manner that the upper ends of the cans or containers are disposed substantially in the same plane. Grease or suitable lubricating material, such as vaseline, is applied in a thin coating to the tops of the cans by the feed roll 53 and the cellophane or other suitable paper is positioned in contact with the upper ends of the cans by means of the feed roll 64. The cans pass inwardly through the machine until they reach a position in which the two 45 foremost adjacent cans are positioned beneath the pressing and cutting mechanism. The presser feet then press the paper into contact with the upper ends of the containers or cans and the cutting mechanism operates to sever the strip between the adjacent containers. This pressing and severing operation is carried on as the containers continue to be fed by the chain and the pressing and severing means is so mounted and actuated that after coating to sever the strip between one pair of adjacent containers, this mechanism will move to a position in which it will coat with the next pair of adjacent containers. After the strip has been severed, leaving a disk of paper or other material on the tops of the cans, the cans are removed from the machine. After removal from this machine, the can covers are crimped around the upper edge of the 55 cans, the paper being positioned between the

covers and the tops of the cans and forming a seal.

From the foregoing specification it will be seen that a simple, practical and efficient machine has been designed for accomplishing the purposes set forth and for applying a sealing disk to containers.

Although one specific embodiment of the invention has been particularly shown and described, it will be seen that the invention 75 is capable of modification and that changes in the construction and in the arrangement of the various cooperating parts may be made without departing from the spirit or scope of the invention, as expressed in the 80 following claims.

What I claim is:

1. In a machine of the character specified, means for supporting and feeding a plurality of containers, means for feeding an elongated strip of material across the ends of the containers and into contact therewith, and means movable with the containers and strip for severing said strip.

2. In a machine of the character specified, means for supporting and feeding a plurality of containers, means for feeding an elongated strip of material across the ends of the containers and into contact therewith, means for holding the strip against the ends of adjacent containers, and means movable with the containers and strip for severing said strip between adjacent containers.

3. In a machine of the character specified, means for supporting and feeding a plurality of containers, means for feeding an elongated strip of material across the ends of the containers and into contact therewith, and mechanism movable with the containers and strip including means for holding the strip against the ends of adjacent containers and means for severing the strip between said adjacent containers.

4. In a machine of the character specified, means for supporting and feeding a plurality of containers, means for feeding an elongated strip of material across the ends of the containers and into contact therewith, and intermittently operable means movable with the containers and strip for severing said strip.

5. In a machine of the character specified, means for supporting and feeding a plurality of containers, means for feeding an elongated strip of material across the ends of the containers and into contact therewith, and intermittently operable mechanism movable with the containers and strip for holding the strip including means against the ends of adjacent containers and means for severing the strip between said adjacent containers.

6. In a machine of the character specified, means for supporting and feeding a plurality of containers, means for feeding an elongated

- gated strip of material across the ends of the containers and into contact therewith, intermittently operable means for holding the strip against the ends of adjacent containers, 5 and means movable with the containers and strip for severing said strip between adjacent containers.
7. In a machine of the character specified, means for supporting and feeding a plurality of containers, means for feeding an elongated strip of material across the ends of the containers and into contact therewith, and continuously actuated means, operable successively between advancing sets of adjacent containers, for severing the strip between said adjacent containers. 10
8. In a machine of the character specified, means for continuously advancing a plurality of containers, means for positioning a continuous strip of material against the tops 20 of said containers, and means movable with said containers and strip and operable between adjacent containers for severing the strip between said containers.
- 25 9. In a machine of the character specified, means for continuously advancing a plurality of containers, means for positioning a continuous strip of material against the tops of said containers, and intermittently operable means movable with said containers and strip and operable between adjacent containers for severing the strip between said containers.
- 30 10. In a machine of the character specified, means for continuously advancing a plurality of containers, means for positioning a continuous strip of material against the tops of said containers, means movable with said containers and strip and operable between adjacent containers for severing the strip between said containers, and means for holding the strip against the ends of the containers during the severing operation.
- 35 11. In a machine of the character specified, means for continuously advancing a plurality of containers, means for positioning a continuous strip of material against the tops of said containers, means movable with said containers and strip and operable between adjacent containers for severing the strip between said containers, and means movable with the strip and containers for holding the strip against the ends of the containers during the severing operation.
- 40 55 12. In combination, means for supporting and feeding a plurality of containers, means for applying viscous material to one end of each container, means for feeding an elongated strip of material across said ends and into engagement therewith, and means movable with the containers and strip and operable toward the longitudinal center of the sheet from the longitudinal edges thereof for severing said sheet at each side of each container.
13. In combination, means for supporting and feeding a plurality of containers, means for applying grease to one end of each container, means for feeding an elongated strip of material across said ends and into engagement therewith, and rotatable means movable with the strip and containers for severing said sheet at each side of each container. 70
14. In combination, means for supporting and feeding a plurality of containers, means for applying grease to one end of each container, means for feeding an elongated strip of material across said ends and into engagement therewith, and rotatable means movable with the strip and containers and operable toward the longitudinal center of the sheet from the longitudinal edges thereof for severing said sheet at each side of each container. 75
15. In combination, means for supporting and feeding a plurality of containers, means for applying grease to one end of each container, means for feeding an elongated strip of material across said ends and into engagement therewith, curved stationary knives positioned above the strip of material and movable knives at the edges of the material adapted to swing between adjacent containers and coact with said stationary knives to sever the strip between adjacent containers, said knives being movable with the strip and containers. 80
16. In combination, means for supporting and feeding a plurality of containers, means for applying viscous material to one end of each container, means for feeding an elongated strip of material across said ends and into engagement therewith, curved stationary knives positioned above the strip of material and curved flexible knives rotatably mounted at the edges of the material adapted to swing between adjacent containers and coact with said stationary knives to sever the strip between the adjacent containers, said knives being movable with the strip and containers. 85
17. In a machine of the character specified, means for supporting and feeding a plurality of containers, means for feeding a continuous strip of material along the tops of said containers and into contact therewith, a carriage, means for moving said carriage with said strip and containers and means mounted on said carriage for severing said strip. 110
18. In a machine of the character specified, means for supporting and feeding a plurality of containers, means for feeding a continuous strip of material along the tops of said containers and into contact therewith, a carriage, means for moving said carriage with said strip and containers, means mounted on said carriage for severing said strip between adjacent containers, and means 125

on said carriage for holding the strip against said adjacent containers during the severing operation.

19. In a machine of the character specified, means for supporting and feeding a plurality of containers, means for feeding a continuous strip of material along the tops of said containers and into contact therewith, a reciprocable carriage, means for moving said carriage with said strip and containers and means mounted on said carriage for severing said strip.

20. In a machine of the character specified, means for supporting and feeding a plurality of containers, means for feeding a continuous strip of material along the tops of said containers and into contact therewith, a reciprocable carriage, means for moving said carriage with said strip and containers, means mounted on said carriage for severing said strip, and reciprocable means on said carriage for holding the strip against said adjacent containers during the severing operation.

21. In a machine of the character specified, means for supporting and feeding a plurality of containers, means for feeding a continuous strip of material along the tops of said containers and into contact therewith, a horizontally reciprocable carriage, means for moving said carriage with said strip and containers, means mounted on said carriage for severing said strip, and vertically reciprocable means on said carriage for holding the strip against said adjacent containers during the severing operation.

22. In a machine of the character specified, means for supporting and feeding a plurality of containers and means for applying viscous material to the tops of said containers, said applying means comprising a roll engageable with said container tops, a receptacle for the material, a roll for feeding the material out of the receptacle and a roll engageable with said feeding roll and said first roll, said rolls decreasing in width from the feeding roll to the applying roll.

23. In a machine of the character specified, means for supporting and feeding a plurality of containers, means for feeding an elongated strip of material across the ends of the containers and into contact therewith, said strip feeding means comprising a plurality of feed rolls having portions of their surfaces coacting to feed the strip and other portions out of coacting relation.

24. In a machine of the character specified, means for supporting and feeding a plurality of containers having open ends, means for feeding an elongated strip of material in the direction of feed of the containers across the open ends of the containers and into flat engagement therewith, said strip feeding means comprising a pair of feed rolls.

25. In a machine of the character specified, means for supporting and feeding a plurality of containers, means for feeding an elongated strip of material across the ends of the containers and into contact therewith, said strip feeding means comprising a pair of coacting feed rolls, one of the rolls having a flat portion in its periphery.

26. In a machine of the character specified, means for supporting and feeding a plurality of containers, means for feeding an elongated strip of material across the ends of the containers and into contact therewith, said strip feeding means comprising a pair of coacting feed rolls, one of the rolls having a portion of its periphery cut away.

27. In a machine of the character specified, means for supporting and feeding a plurality of containers, means for feeding an elongated strip of material across the ends of the containers and into contact therewith, said strip feeding means comprising three interengaging rolls, each of the two rolls at the side of the central roll having a portion of its periphery cut away.

28. In a machine of the character specified, means for supporting and feeding a plurality of containers, means for feeding an elongated strip of material across the ends of the containers and into contact therewith, said strip feeding means comprising three interengaging rolls, each of the two rolls at the side of the central roll having a portion of its periphery cut away, said cut away portions being so located that only one of said portions will be positioned opposite the central roll at any one time.

29. In a machine of the character specified, means for supporting and feeding a plurality of open ended containers, said means comprising an endless carrier and a plurality of spaced supports thereon, each support being adapted to receive one container, a chute for feeding the containers to said carrier and means disposed above the delivery end of the chute for positioning and holding the containers on said supports.

30. In a machine of the character specified, means for supporting and feeding a plurality of open ended containers, said means comprising an endless carrier and a plurality of spaced supports thereon, each support being adapted to receive one container, a chute for feeding the containers to said carrier and resilient means disposed above the delivery end of the chute for positioning and holding the containers on said supports.

31. In a machine of the character specified, means for supporting and feeding a plurality of open ended containers, said means comprising an endless carrier and a plurality of spaced supports thereon, each support having a beveled upper end and being adapted to receive one container, a chute

for feeding the containers to said carrier and means disposed above the delivery end of the chute for positioning and holding the containers on said supports.

5 32. In a machine of the character specified, means for supporting and feeding a plurality of open ended containers, said means comprising an endless carrier and a plurality of spaced supports thereon, each

support having a beveled upper end and being adapted to receive one container, a chute for feeding the containers to said carrier and resilient means disposed above the delivery end of the chute for positioning and holding the containers on said supports. 10

In witness whereof, I have hereunto set my hand this 29th day of October, 1926.

JOHN VAN BUREN.
